UNITED STATES PATENT OFFICE.

JOHN P. PUGH AND WILLIAM C. CLARK, OF SHREVEPORT, LOUISIANA.

WELL PACKER.

Application filed March 19, 1927. Serial No. 176,646.

The object of this invention is to provide a well packer suitable for use in oil, gas and water wells, for the purpose of ascertaining, after the drilling has proceeded to what is deemed a proper depth, whether the well is of such a nature as to warrant its completion.

This packer is adapted for use before any casing is set in the well, and thereby enables the driller to determine the probable value of the well without necessitating the expense of setting the well casing.

The invention consists, broadly, in a well packer, including a bearing tube provided at one end with means for connecting it to and suspending it from a string of drill rod or tubing, and having at its other end means for connecting to it the perforated liner generally used in drilling operations, and a packer member slidably mounted upon the tube and having its sliding movement relatively thereto limited by these connecting means, combined with a frangible diaphragm arranged to close the tube to normally prevent passage therethrough and into the string of drill tubing of mud, water and other substances contained in the well, the breaking of this diaphragm presenting an open passage from the bottom of the well to the surface of the ground, as we will proceed now to explain and finally claim.

In the accompanying drawings illustrating the invention, in the several figures of which like parts are similarly designated, Fig. 1 is an elevation of the packer with its parts in the positions assumed while it is being lowered into the well. Fig. 2 is a longitudinal axial section showing the parts in the position assumed when the packer has come to a seat.

The packer comprises, essentially, a bearing tube 1, provided at one end, its normally lower end, with a collar 2 screwthreaded or otherwise prepared as at 3 to have connected to it the usual perforated liner 4 terminating in a "bull plug" 5. At its other, or normally upper, end the tube 1 is preferably threaded to receive a coupling member 6 whereby the packer may be connected to a string of drill rod or tubing 7, only a portion of which is shown.

Within the coupling member 6, and between a shoulder 8 therein and a follower ring 9, is mounted a frangible diaphragm 10, of glass or some other relatively strong material which may be shattered by a blow.

This diaphragm is placed between appropriate washers or packing rings 11.

Mounted upon the tube 1 between the collar 2 and coupling member 6, and having a relatively easy sliding fit on said tube, is a sleeve 12 provided with a shoulder 13 and carrying a packer member 14, preferably composed of a plurality of circular perforated disks or rings of rubberized fabric or other partially compressible or rigid material stacked one above the other against the shoulder 13. The packer member may be cylindrical, or it may be frusto-conical as desired, or as circumstances demand. This packer member is securely held upon the sleeve 12 by means of a nut 15 which is screwed down tight upon the top of the packer member by means of its threaded connection 16 with the upper end of the sleeve. This nut is provided with a gas- 70 ket 17 which intimately engages the tube 1, and the nut has sockets 18 in its sides for the reception of a spanner wrench by which it may be adjusted.

The parts 2, 6 and 15 may be knurled as at 80 19, if desired, to present a good frictional surface for engagement by a wrench or other turning or securing tool.

In order to facilitate the removal of the packer from the well, after it has served its purpose, as will be hereinafter explained, the tube 1 is provided with a number of openings 20, these openings being covered by the sleeve 12 when the packer is seated, and uncovered when it is being raised or lowered. 90

In drilling wells for oil, gas or water, it is customary to drill a hole 21 of a diameter approximating nine inches to such a depth as the driller believes will bring the hole in proximity to the oil, gas or water-bearing stratum, and then to continue drilling for a short distance with a drill of less diameter, say approximately six inches, until it is thought that the oil, gas or water-bearing stratum has been reached. The hole thus drilled will therefore have its greatest depth of one diameter, and its lowermost portion of a smaller diameter, thus forming a shoulder 22, as shown in the drawings.

The portion 23 of the hole drilled last and of a smaller diameter, is called a "rat hole" and it is into this "rat hole" that the oil, gas or water first flows. Our packer is designed to seal this "rat hole" from the main bore of the well so that the mud and other substances contained therein may not enter the "rat hole" and the substances contained in the

"rat hole" may be extracted and a test made of the well, or so that the well may be bailed or experimentally operated.

In using our packer we proceed substantially as follows:—The string of drill tubing is withdrawn from the well, the drill is disconnected therefrom, and the packer applied in place of the drill by means of the coupling member 6, as shown. Then the packer is lowered into the well, the parts of the packer assuming the positions shown in Fig. 1, with the packer-member 14 and the lower end of the sleeve 12 resting upon the collar 13. When the packer-member passes partially into the "rat hole" its body will find a seat at the shoulder 22 and the weight of the packer and string of tubing will firmly wedge the packer member into the "rat hole", the bearing tube meanwhile sliding downwardly through the sleeve 12 until the coupling member 6 comes into contact with the nut 15, as shown in Fig. 2. This adjustment of the tube 1 will cover the openings 20, and it will thus be seen that the "rat hole" 23 is completely sealed from the rest of the well bore 21.

Obviously, the packer will be completely surrounded by mud and the like, both in the portion 21 of the bore and in the "rat hole" 23, and this mud must be removed before a test can be made.

In order to remove the mud and make the test, the diaphragm 10 must be broken, and this is done by lowering a bailer or other heavy implement in the spring of tubing 7, so that it strikes against the diaphragm. After the diaphragm has been broken it will be seen that an unobstructed passage is formed from the bottom of the "rat hole" to the surface of the ground. This passage enables the driller to bail the "rat hole", take samples of what has been struck, or operate the well experimentally to determine its yield without going to the labor and expense of setting a well casing.

When it is desired to remove the packer, it is simply raised by raising the drill tubing 7, and if it has become stuck it may be dislodged by giving it a sharp rap or two by raising and lowering the tube 1 so that the collar 2 strikes sharply against the bottom of the sleeve 12.

As the packer is raised out of the well it assumes the position shown in Fig. 1 with relation to the tube 1, thus uncovering the openings 20, and if difficulty is experienced in pulling it, water may be forced down the tubing 7, and this water escaping through the openings 20 will, in a sense, lubricate the packer and facilitate its withdrawal.

Our packer is simple and sturdy in construction, lends itself readily to replacements and repairs being easily taken apart and assembled, and is relatively inexpensive to manufacture.

Obviously, the packer may be left at the bottom of the well for as long a period as desired, and a pumping device may be connected with it and the well thus operated, thereby insuring a thorough test of the capacity of the well before it is put on standard equipment or abandoned.

Various changes are contemplated as within the spirit of the invention and the scope of the following claim.

What we claim is:—

In a well packer, a bearing tube having upper and lower stops and perforations between said stops, a packer sleeve slidable on the tube between said stops and arranged to normally uncover said perforations, and to cover the same when the sleeve is slid upwardly, and a frangible partition, at the upper end of the tube, above said perforations.

In testimony whereof we have hereunto set our hands this 15th day of March A. D. 1927.

JOHN P. PUGH.
WILLIAM C. CLARK.
